Ervin Schuler & Moulard ATTORNEYS.

UNITED STATES PATENT OFFICE.

DAVID W. HUDSON, OF GREEN BAY, WISCONSIN.

INTERFOLDED PAPER PACKAGE AND PROCESS OF MANUFACTURING SAME.

1,381,307.

Specification of Letters Patent. Patented June 14, 1921.

Application filed October 5, 1920. Serial No. 414,924.

To all whom it may concern:

Be it known that I, DAVID W. HUDSON, a citizen of the United States, residing at Green Bay, county of Brown, and State of 5 Wisconsin, have invented new and useful Improvements in Interfolded Paper Packages and Processes of Manufacturing Same, of which the following is a specification.

My invention relates to improvements in 10 inter-folded paper packages and processes of manufacturing the same.

Such packages have heretofore been made by first cutting strips of paper into sheets which were wholly separated from each 15 other and subsequently folding the sheets in such a manner that each embraced the ends of two other sheets which were held in position merely by frictional contact with the folded sheet.

20 Considerable difficulty has heretofore been experienced in handling the sheets of paper during the folding operation and preventing them from becoming displaced from their proper relation to each other, either prior 25 to their engagement with the companion folded sheets or subsequently during the operation of packaging the inter-folded sheets, or of feeding them from an inter-folding machine.

30 The object of my invention is to provide means whereby the sheets may be sufficiently retained in proper relation to each other during the inter-folding, feeding and packaging operations to prevent displacement 35 and insure that the completed package will have all of its sheets properly inter-folded.

A further object of my invention is to provide means for insuring the production of a perfectly interfolded package of sheets.

40 Further it is my object to produce an improved package in which the delivery of one sheet will more uniformly and certainly release a portion of the next sheet in a duplex series of inter-folded sheets and expose it 45 in a position where it can be readily grasped and removed while exposing a third sheet in similar manner by partially drawing it from the package or from within a cabinet in which the package has been placed.

50 In the accompanying drawing Figure 1 illustrates in perspective the various stages of my process, showing the same as it is being continuously performed for successively inter-folding sheets and for produc- 55 ing successive packages.

Fig. 2 illustrates two successive sheets of

one series in proper relation to two other sheets in a companion series, each of said sheets having dotted lines indicating the manner in which they are to be folded. 60

It will be observed in Fig. 2 that the sheets in each series are connected with each other by a narrow tongue of paper along one margin of the strip from which the sheets are cut. For example: The sheets 1 and 2 65 illustrated in Fig. 2 are in one series, i. e., a continuous strip of paper which has been partially cut across at 3 leaving the sheets integrally connected by a narrow tongue 4. The sheets 5 and 6 of the adjacent series or 70 opposing series are connected with each other by similar tongues 7, these sheets being formed by partially severing the strip of which they are a portion and feeding them into such relation to the sheets 1 and 75 2 that the tongues 4 in one series are midway between the tongues 7 in the opposing series.

The two strips of paper or series of sheets above described, are delivered from between 80 suitable guiding or feeding devices, such for example as the rollers 10 illustrated in Fig. 1. As a sheet 1 passes from between these rollers it is tucked between a pair of folding jaws 12 and 13 conventionally illustrated in Fig. 1, the jaws receiving the paper substantially at its transverse center line and being subsequently closed upon it to form a crease. The folded halves of the sheet embrace the ends of two sheets 5 and 90 6 in the adjacent series. These ends are tucked into the jaws simultaneously with the sheet to be folded, preferably by a tucker blade such as indicated at 15 in Fig. 1, the connecting tongue 4 (or 7) enabling the 95 tucker blade to carry the ends of the inter-folded sheets between the jaws with certainty, both as to the relation to the sheets to be inter-folded and as to their relation to each other, with their end margins substantially in abutting contact from the connecting tongue to the opposite side margins of the respective sheets.

Subsequently to the folding operation above described, the feeding rollers 10 are 105 moved to the dotted line position indicated in Fig. 1, and the folding operation repeated upon the sheet 5 which is tucked between jaws 17 and 18, similar to the jaws 12 and 13, but oppositely disposed, and so positioned as to receive the sheet 5 between them 110 substantially at its transverse center line,

and also to receive one end of the sheet 1 and the adjacent end of the succeeding sheet 2 in the series to which the sheet 1 belongs.

After each inter-folding operation, the folded sheets are pressed downwardly to form a pile 20 and by allowing this pile to move downwardly in a curved chute 21 a continuous series of folded sheets may be delivered upon a table 23, which is preferably horizontally disposed and which supports the folded sheets, as clearly shown in Fig. 1, in positions which facilitate their separation at desired points indicated by the arrows 25 and 26.

I have found that the connecting tongues of paper 4 and 7 not only enable me to inter-fold the sheets accurately and properly with unvarying success, but that they also hold the sheets in their proper inter-folded relation while the sheets are being pushed outwardly upon a table, and while they are being separated into packages at the points indicated by the arrows, and subsequently inclosed in bands or wrappers for the purpose of shipment.

Great importance is attached to the fact that the connecting tongues 4 and 7 are uniformly located along one margin of each of the strips and are of just sufficient width to hold the sheets in position while carrying out the inter-folding process without offering sufficient resistance to tearing strains to allow more than one sheet to be pulled from the package at a time when the package is separated in a container of ordinary type.

I have found by experiment that connecting tongues at the side margins of about $\frac{1}{8}$ " in width will be sufficient for my purposes under ordinary conditions, although the width of the tongue may be varied to some extent in accordance with the quality of the paper, wider tongues being possible with paper that is easily torn whereas if the paper is less easily torn the width of the tongue will be correspondingly diminished. I have also found that where the tongues are located along one side margin the exposed sheet of paper will pull obliquely thereon and the tearing operation will commence at one side of the tongue and continuously progressively to the other

side, the fibers of the paper giving away successively and with much less pull upon the next succeeding sheet in the package than would be the case if the connecting tongues were located along the longitudinal center lines of the respective strips.

I am therefore able to produce a much more perfect package of inter-folded sheets than has heretofore been possible without extraordinary expense, and I am also able to deliver sheets from such packages successively and uniformly as single sheets with the same certainty as heretofore in the delivery of separated sheets, but with increased certainty that the next succeeding sheet will be drawn down so as to expose half of it to facilitate its subsequent withdrawal from the package or from the package containing cabinet.

I claim:—

1. The process of manufacturing packages of interfolded paper sheets, consisting in uniformly slitting paper strips along transverse lines to nearly sever the strip, while leaving narrow connecting tongues along one margin of each strip integrally connecting the sheets, and subsequently arranging the sheets in the respective series in break joint relation and folding the sheets of one series in one direction and those of the other series in the opposite direction, with each sheet embracing near its folding line the partially severed ends and connecting tongue of two sheets in the other series.

2. A package of interfolded paper sheets comprising two series of sheets, integrally connected along one side margin by a narrow tongue, and severed from each other along a line extending from said tongue to the opposing side margin, said sheets in each series being in break joint relation to those of the other series and folded upon them with the partially severed margins embraced along the folding line.

In testimony whereof I affix my signature in the presence of two witnesses.

DAVID W. HUDSON.
